CHRISTIAN A. SELANDER, OF RENTON, WASHINGTON

COMBINATION TABLE AND IRONING BOARD

Application filed October 22, 1927. Serial No. 227,875.

The invention is a combination table and ironing board in which the ironing board is made in the top of the table so that it may be folded within the limits of the table which 5 will enable the device to be used as a table or ironing stand.

The object of the invention is to provide a piece of furniture that is adaptable to be used as a table or as an ironing board.

10 Another object of the invention is to provide an ironing board which will be located in a very convenient position so that it is always readily accessible.

Another object of the invention is to provide 15 a table having an ironing board built in the top thereof.

A further object of the invention is to provide means for forming an ironing board in the top of a table so that when the device is 20 folded it will be impossible to see the ironing board.

And a still further object of the invention is to provide a combination table and ironing board which is of a simple and economical 25 construction.

With these ends in view the invention embodies a table in which the cover is divided into sections with one section hinged to another and an ironing board formed on the 30 under side of one section which is adaptable to be opened so that the ironing board will be in a position in which it may readily be used. The remaining section of the cover may also be hinged and an inclosure may 35 be provided under it in which the iron and cord or other objects may be placed.

Other features and advantages of the invention will readily be seen from the following description, taken in connection with the 40 drawings wherein:

Figure 1 is a side elevation of the table.

Figure 2 is a similar view showing the ironing board ready for use.

Figure 3 is a cross section through the 45 table.

Figure 4 is an end view showing the ironing board and hinged section of the table cover as they may appear when being opened or closed.

50 In the drawings the device is shown as it

would be made wherein numeral 1 indicates the table, numeral 2 the ironing board and numeral 3 the compartment under the table cover.

The table 1 may be of any suitable design 55 or construction and may be provided with legs 4 with cross members 5 between them to hold their upper ends rigid. One section of the cover which is indicated by the numeral 6 may be rigidly attached to the legs 4 and 60 the members 5 and the section 7 at the opposite side may be hinged to the upper ends of the legs by hinges 8 as shown in Figure 3. The intermediate section 9 may be hinged to the edge of the section 6 by hinges 10 and an 65 ironing board as indicated by the numeral 11 may be attached to the under side of the section 9 by a support 12. It will be observed that with the section 9 hinged to the section 6 it may readily be opened and moved from the 70 position shown in full lines in Figure 3 to the position shown in dotted lines, and it will be observed that when it is in the position shown in full lines the device may readily be used as a table and when it is in the position 75 shown in dotted lines it may be used as an ironing board. At the opposite side of the table and below the section 7 is a cross member 13 and another member 14 forming a bottom which form an inclosed space 3 in 80 which the iron or other objects may be placed.

The hinge 10 may be of any suitable design or arranged in any suitable manner to permit the section 9 with the ironing board to swing upward so that it will rest flat upon the upper 85 surface of the section 6, and so that it will not project above the surface of the table when the ironing board section is closed.

It will be understood that changes may be made in the construction without departing 90 from the spirit of the invention. One of which changes may be in the design of the table as it is understood the panel containing the ironing board may be made in a table of any suitable design, another may be in the design of the ironing board or in the use of other means for supporting it from the panel, another may be in the omission of the hinges 10 so that the ironing board or panel upon 95 which it is mounted may be free so that they 100

may be placed in any suitable position, and still another may be in the use of other compartments arranged in the table which may be located in the ends, sides or at any other suitable position.

The construction will be readily understood from the foregoing description. In use the device may be used as a table and when it is desired to use the ironing board the panel or section 9 may be raised as shown in Figure 4 and placed in the position shown in dotted lines in Figure 3, and also as shown in Figure 2. The iron with the cord and a pad for the ironing board may be kept in the compartment 3 and the cover 7 may readily be opened so that they may be used as desired. It is also understood however that these objects may be kept in any other suitable location and also that any other objects may be placed in the compartment 3 or any other similar compartments on the table.

Having thus fully described the invention, what I claim as new and desire to secure by Letters Patent, is:—

25 In a table of the character described, a table having a plurality of longitudinal panels forming the top thereof, one of said panels being stationary, means for hinging an intermediate panel to the said stationary panel, a panel at the side opposite the stationary panel forming a rest for material being ironed, and an ironing board on the under side of said intermediate panel, said intermediate panel adapted to raise and rest on said stationary panel.
